PIRN WINDER OR THE LIKE

Harold Lionel Muschamp, Bramhall, and John Robert Grady, Cheadle Hulme, England; said Grady assignor to said Muschamp

Application August 13, 1952, Serial No. 304,084
In Great Britain August 15, 1951

4 Claims. (Cl. 242—34)

1

This invention relates to winders for pirls and like packages built up from one end and in particular to feeler-controlled traverse feed mechanism therefor of the kind comprising a traverse feed screw with mechanism for turning the same to advance the carriage of a reciprocating yarn guide progressively as the package, following each preceding advance, reaches a predetermined diameter as determined by a controlling feeler.

There are many known constructional forms of feeler-controlled feed traverse mechanism of the kind aforesaid, the feeler being usually in the form of a rotatable disc, adjustable for setting at a predetermined distance from the winding axis, and advancing with the carriage so as always to be presented to that portion of the package being wound at the base end of the traverse.

In such mechanisms, contact of the feeler with the yarn on the package is essential for activating the feed mechanism and with the modern trend for the use of yarns such as rayon yarns of very fine filaments or fibres every effort is made to increase the sensitivity of the feeler and to reduce to a maximum the frictional contact of the feeler with the yarn, such contact even when quite light being known to cause damage to the yarn by polishing the same with resultant visible marking or "barring" in any fabric woven therefrom. Another problem which has become more acute owing to the relatively slippery nature and fineness of the aforesaid synthetic yarns of the present day, is the incidence of "soft nose" effect when using a feeler-controlled traverse for the winding mechanism.

In some known mechanisms, contact of the feeler with the package is used to effect physical movement of some part of the feed mechanism, for example to turn a light worm or, in the case of a pawl-actuated mechanism for rotating the feed screw, to advance a lever or finger into the path of some moving part until engagement therewith results in actuation of the feed advance mechanism. Any such mechanism entails the extraction of a working effort from contact between the feeler and the package the amount of work being the product of the force and the distance through which it has to move, even if only to move it into the path of an actuating member.

The object of the present invention is to reduce any factor of work to a minimum by increased sensitivity of the feeler mechanism, and thereby substantially to eliminate the problems aforesaid.

2

According to the invention feed traverse mechanism for a pirl winder comprises a traverse feed screw, driving means for said feed screw including a resiliently loaded friction brake drive controlling device and a feeler located between said pirl and said controlling device whereby contact of the feeler with the pirl relieves part of the load on the friction brake to permit momentary driving of the feed screw.

10 In the accompanying drawings:

Fig. 1 is an end elevation;

Fig. 2 is a plan of one example of a feeler controlled traverse feed mechanism made in accordance with the present invention, and

15 Fig. 3 is a diagram showing a modification.

As shown in the drawings *a* and *b* are the headstock and tailstock respectively of a pirl winder the latter mounted on a rod *c*, a partly wound pirl *d* being shown in position. Parallel with the rod *c* is a further rod *e* and a carriage *f* for the reciprocating yarn guide (not shown) is slidably mounted on these two rods. Pivotedly mounted on said carriage is lever *f*¹ carrying a nut element *f*² urged outwardly from the carriage 20 by a spring *f*³. On the opposite side of the rod *e* from the rod *c* is a feed screw *g* of the usual construction and engageable by the said nut element on the front end of which feed screw is mounted a ratchet wheel *h*. At the front end 25 of the winding machine is a crank *i* shown diagrammatically in isolation from the winding station, which is connected by a link *j* to a ratchet arm *k* pivotally mounted on the end of the feed screw, said arm carrying a pawl or ratchet *m* complimentary to the ratchet wheel *h*. Also rotatably mounted on the feed screw is a mask *n* for the ratchet wheel which has a secondary mask-like portion *n*¹ located on the inner side 30 of the front frame of the winder.

35 Pivotedly mounted on a rod *o*, parallel to the feed screw is a U-shaped former *p* having at its rear end an adjustable base-turns former *p*¹ the former being urged by a light spring *q* towards the winding centres. Slidably mounted 40 in a bracket *f*⁴ on the carriage *f* is a two-part feeler *r* slightly inclined from the right angles to the winding axis as shown in Fig. 2, carrying a freely rotatable feeler wheel *r*¹ at the end and having a feeler nose *r*² at the other end normally 45 in sliding engagement with the edge of the former *p* or *p*¹. The former carries a pad *p*² which engages frictionally with the mask-like portion *n*¹ aforesaid. The mask *n* has a projecting tongue *n*² adapted to be engaged by the arm *k*.

50 55 In operation, the crank is rotated continuously

during the winding operation and imparts a reciprocating motion to the pawl arm k . Unless the mask is in the position shown in the drawings the arm k will raise it to such position by engaging the tongue n^2 and the friction pad p^2 engaging the mask-like portion n^1 under the effort of the light spring q will just hold the mask in such position against the action of gravity and any light return drag of the pawl m . The nose r^2 of the feeler rides against the edge of the former p or p^1 and the least pressure on the disc r^1 from the bobbin d causes the force of the light spring q to be divided part being taken now by the nose r^2 as well as by the pad p^2 . In consequence the mask n slips round under the force of gravity and on the next upward movement of the pawl arm k the pawl will overhang the upper end of the mask so as to engage the ratchet wheel and turn the feed screw. The mask is simultaneously raised to its normal position and remains there until released, the pawl at the upper end of each stroke merely dropping over the end of the mask to engage the ratchet wheel but without moving the same.

The mechanism above described may be the sole means for turning the feed screw or may be supplemental to a main ratchet feed set to provide a continuous traverse feed just short of that actually required for the bobbin being wound.

In the modification shown in Fig. 3 in addition to the feeler controlled mechanism for advancing the feed screw as shown in Figs. 1 and 2 but represented diagrammatically by the crank i , link j , pawl m carried by the arm k and the mask n there is a link j^1 connected to the crank i , pawl m^1 carried by the arm k^1 and mask n^1 the latter being adjustably secured in any desired position by a screw n^3 located in an arcuate slot n^4 . The mask n^1 can thus be set so that the pawl m^1 advances the feed screw a positive number of teeth with each rotation of the crank i intermittently with any permitted advance of the feed screw by the pawl m . Such positive and continuous advance may be set, as previously stated, so as to be just less than or short of that required for the build up of the bobbin according to the gauge of the yarn. Also the pawl m may have a tension spring s which enables the pawl to be turned onto its back into an in-

operative position leaving the advance of the feed screw to be effected solely by the pawl m^1 , while the pawl m^1 may similarly be adapted for movement into an inoperative position leaving the feeler controlled pawl alone to effect the advance of the feed screw. When both advancing means are used as above described the contact of the feeler wheel with the bobbin will, therefore, be less frequent as the feeler-controlled feed will only be required to make up the said shortage of the main traverse movement.

What we claim is:

1. Feed traverse mechanism for a pinc winder comprising a traverse feed screw, driving means for said feed screw including a resiliently loaded friction brake drive controlling device and a feeler located between said pinc and said controlling device whereby contact of the feeler with the pinc relieves part of the load on the friction brake to permit momentary driving of the feed screw.
2. Feed traverse mechanism for a pinc winder according to claim 1 characterised in that the driving means for the feed screw comprises a reciprocating ratchet and ratchet wheel, a mask for said ratchet wheel, means for moving said mask to uncover said ratchet wheel when released by the brake device and means associated with the reciprocating ratchet for returning the mask into an operative position simultaneously with the rotation of the ratchet wheel so that such mask may be retained in such position by the friction brake device if permitted by the feeler.
3. Feed traverse mechanism according to claim 1 characterised by further and adjustable driving means for the feed screw for continuous advance thereof so arranged that the feeler controlled advance is supplemental thereto.
4. Feed traverse mechanism according to claim 2 characterised by a second reciprocating ratchet engageable with the ratchet wheel and an adjustable mask therefor so arranged that it can operate alternately with the feeler controlled ratchet whereby a continuous predetermined advance can be given to the feed screw and the feeler controlled advance will be supplemental thereto.
